CANDLE MOLD

Zachary P. Abuza, 19425 Van Aken 44122, and Stanley W. Morgenstern, 2887 Broxton 44120, both of Shaker Heights, Ohio

Filed Jan. 26, 1972, Ser. No. 221,122

Term of patent 14 years

Int. Cl. D15—09
U.S. Cl. D55—1 F

FIG.1

FIG.2

FIG.5

FIG.3

5 → FIG.4

FIG. 1 is a perspective view of the candle mold embodying our new design;

FIG. 2 is a side elevation view of the candle mold embodying our new design with the opposite side being a mirror image thereof;

FIG. 3 is a top plan view of the candle mold embodying our new design;

FIG. 4 is a transverse view taken along the line 4—4 of FIG. 3; and

FIG. 5 is a transverse view taken along the line 5—5 of FIG. 4.

We claim:

The ornamental design for a candle mold, as shown and described.
